UNITED STATES PATENT OFFICE.

CLARENCE H. BERRY, OF ISLIP, NEW YORK, ASSIGNOR TO WESTERN ELECTRIC COMPANY, INCORPORATED, OF NEW YORK, N. Y., A CORPORATION OF NEW YORK.

SELECTOR SWITCH.

Application filed November 21, 1924. Serial No. 751,217.

This invention relates to telephone apparatus of the automatic type and more particularly to selector switches used in automatic telephone exchange systems wherein

5 a call from a calling subscriber's line is routed through a selector switch by a common sender mechanism.

One of the objects of this invention is to provide a circuit for automatically returning 10 to normal a selector switch which has been moved off normal by hand or advanced falsely with the brush shaft off normal.

Another object is the employment of a 15 circuit which makes it possible for a single revolution of the sequence switch associated with a selector switch to take care of two successive calls.

Heretofore if selector switches were abnormally operated by the jarring of the 20 mechanism during normal operation of the associated parts or the carelessness of workmen, the switches were manually restored to normal. This necessitated the employment of attendants whose duty was to restore abnormally operated selector switches. 25 In accordance with one of the objects of the present invention such conditions are obviated by providing means for the automatic restoration of abnormally operated switches. A sequence switch forming part 30 of the control circuit of a selector switch which utilizes all of its positions, that is, takes a single complete revolution for each call in which the selector is employed is 35 well known in the art. However, by providing, in accordance with the present invention, a circuit which makes it possible to double the call capacity of a selector sequence switch by utilizing a single revolution 40 of the switch for making two successive calls, the wear on the sequence switch is halved thus doubling the life of the switch.

In order that the present invention may 45 be more readily understood, the characteristic features of the portions of the automatic telephone exchange system to which the present invention relates, will be briefly described, the system being described in detail 50 in the patent to F. A. Stearn, No. 1,505,171, issued Aug. 19, 1924. For this purpose reference may be had to the accompanying drawing which shows diagrammatically calling and called subscribers' lines, a line

switch, sender, district, incoming and final 55 selectors, and in detail the circuit of an office selector embodying the features of the present invention.

A calling subscriber upon removing his receiver from the hook is connected to a 60 line switch of which there is one for each line connected to the exchange. The line switch automatically selects an idle circuit which leads to a district selector. As soon as the line switch selects a non-busy district 65 circuit, a sender selector automatically selects a sender. The operation of the dial at the calling subscriber's station stores the impulses representing the exchange and line number wanted on registers in the 70 sender referred to above. The sender having received and stored all of the impulses from the dial automatically controls the setting of the district selector to select an idle trunk going to the desired office. The 75 sender then controls the setting of an office selector in which the selected trunk terminates, which locates an idle trunk to an incoming selector in the distant office. The incoming selector is then controlled by the 80 sender to choose a final selector on which the desired number is located, the final selector then being operated to select the desired line. The various sender registers control the choice of the desired number. There 85 is only one part of this automatic telephone exchange system above outlined which properly constitutes the present invention, that is, the office selector circuit employing a sequence switch which automatically returns 90 to normal and is capable of carrying through two successive calls in a single revolution. The sequence switch used therein is of the type described in the patent to J. N. Reynolds and C. F. Baldwin 1,127,808 95 issued February 9, 1915.

By means of this invention, if a selector is moved off normal by hand or in some other manner with the brush shaft off normal, a relay operates by means of an energizing circuit prepared by the off normal condition which in turn energizes the sequence switch magnet moving the sequence switch to the next position when the relay releases. In this position of the sequence 100 switch an energizing circuit is closed which advances it to the next position where said relay again operates. This cycle is repeated 105

until that position of the sequence switch is reached in which the down drive magnet of the selector is energized, causing the brush shaft to return to normal. This normal condition of the brush shaft closes an energizing circuit which advances the sequence switch to a normal position.

Means are provided in this invention for automatically controlling a cycle of circuit changes in a definite sequence for controlling the selector by means of a sequence switch, one revolution of which takes care of two cycles for two successive calls.

The operation of the circuit is as follows: 15 Upon the calling subscriber at A removing his receiver from the hook, and dialing his number, a district selector is connected to terminals 105, 106, and 114 of the office selector in a manner well known in the art. In the 20 present invention this occurs when the sequence switch is in normal positions 1 or 10. A fundamental circuit is closed from grounded battery 100, through the left contact of cam 101, left winding of relay 102, the lower 25 left contact of cam 103, the left contact of cam 104 over the tip side of the fundamental circuit to the associated district and sender circuits, back over the ring side of these circuits through right lower contact of cam 107 to ground, operating relay 102. The operation 30 of relay 102 closes an energizing circuit for the sequence switch magnet 108 which may be traced from ground controlled by the district sleeve terminal 114, the upper 35 contact of cam 109, contact 110 of operated relay 102, lower right contact of cam 111, through the sequence switch magnet 108, battery 112 to ground, the sequence switch 40 advancing to position 2 or 11. As the switch enters position 2 or 11, ground from the left and right upper contacts of cam 109 is connected to the district sleeve terminal 114 holding the office selector trunk busy to all 45 other district selectors. This busy ground is effective in positions 2 to 2½ and 3½ to 7 or 11 to 11½ and 12½ to 16. In positions 2½ to 3½ or 11½ to 12½, the busy condition is produced by the resistance of the right winding of relay 102 to ground at cam 129. 50 The relay 102 is now held operated over the fundamental circuit over the upper left contact of cam 103, armature springs 138 and 132 and left winding of relay 102 to battery at the left contact of cam 101.

In position 2 or 11, the up drive magnet 118 of the selector is energized for brush selection. This energizing circuit goes from ground through the left contact of cam 109, contact 110 of operated relay 102, the right 55 upper contact of cam 111 through up drive magnet 118, battery 119 to ground. As the brush shaft moves upward, a circuit is closed from ground over the lower contacts of cam 129, commutator brush 121, commutator segment 120, and upper contacts of cam 103

over which ground pulses are sent back over the fundamental circuit to successively short circuit and permit the reoperation of the stepping relay in the associated sender circuit until the proper brush has been selected. 10 When sufficient pulses have been sent back to satisfy the sender, the fundamental circuit is opened and relay 102 releases. The release of relay 102 opens the circuit through up drive magnet 118 which deenergizes and 15 stops the upward movement of the switch shaft. The release of relay 102 also closes an energizing circuit for the sequence switch magnet 108 which may be traced from ground through the left contact of cam 109, normally closed contact 122 of relay 102, right lower contact of cam 123, through sequence switch magnet 108 to battery 112 and thence to ground. The sequence switch advances to position 3 or 12. 20 When the switch reaches position 2½ or 11½, ground from the district sleeve is closed through both upper contacts of cam 125 to hold the right winding of relay 102, shunted at this time.

When the switch reaches position 3 or 12, the fundamental circuit is again closed through the left winding of relay 102. Relay 102 operates and closes an energizing circuit for sequence switch magnet 108, the switch advancing to position 4 or 13 for 25 group selection. The energizing circuit for sequence switch magnet 108 may be traced from ground through left contact of cam 109, contact 110 of operated relay 102, lower right contact of cam 111, sequence switch magnet 108, battery 112, thence to ground. The trip magnet 126 is energized in positions 3 to 5 or 12 to 14 from ground through both lower contacts of cam 109, trip magnet 126, battery 119, and thence to ground. With the switch in positions 4 or 13, relay 102 is held 30 operated over its left winding and left contacts 132, 138, the left contact of cam 103 and the fundamental circuit as traced, and the up drive magnet 118 is again energized from ground through the left contact of cam 109, contact 110 of operated relay 102, right upper contact of cam 111, through the up drive magnet 118, battery 119, to ground. The trip magnet 126 being operated causes 35 the previously selected brush to trip as the brush shaft moves upward for group selection.

As the brush shaft moves upward for 40 group selection, a circuit is closed from ground at cam 129 through commutator brush 135 and commutator segment 133, the upper right contact of cam 104, over which ground pulses are sent back over the fundamental circuit thus successively short-circuiting and permitting the reoperation of the stepping relay in the associated sender circuit until the proper group has been selected. When sufficient pulses have been sent back to satisfy the sender, the funda- 45

mental circuit is opened, releasing relay 102. The release of relay 102 opens the circuit through the up drive magnet 118 and closes a circuit for advancing the sequence switch 5 to position 5 or 14, the energizing circuit for the sequence switch magnet 108 being the same as that traced for advancing it to position 3 or 12.

With the sequence switch in position 5 10 or 14, a circuit is closed from ground through the lower left and upper right contacts of cam 129, right winding of relay 102, resistance 115, battery 117, to ground, operating relay 102. The operation of relay 102 15 closes an energizing circuit for the sequence switch magnet 108 which is similar to that traced for position 3 or 12. The sequence switch advances to position 6 or 15. When the sequence switch reaches position 6 if the 20 first trunk of the group in which the selector hunts is busy, relay 102 is held operated through its left winding to ground on the sleeve terminal 141 of the busy trunk. This circuit may be traced from ground on sleeve 25 terminal 141 of the trunk, brush 140, conductor 131, through the right contact of cam 130, contact 132 of operated relay 102, the left winding of that relay, the left contact of cam 101, battery 100 to ground. As long 30 as relay 102 is held operated due to this busy condition, the circuit to the up drive magnet 118 is maintained from ground through the left contact of cam 109, contact 110 of operated relay 102, upper right 35 contact of cam 111, the up drive magnet 118, battery 119 to ground, and the brush shaft will travel upward until an idle trunk is found. When an idle trunk is found, the 40 circuit through the left winding of relay 102 is opened but the relay will not release immediately, due to a holding circuit being closed from ground on commutator segment 127 and commutator brush 128, through both upper contacts of cam 129, 45 right winding of relay 102, resistance 115, battery 117 to ground. When the circuit through commutator segment 133 is opened upon the switch brushes becoming properly centered on the terminals of the selected 50 trunk, relay 102 releases, opening the circuit through the up drive magnet 118, which stops the selector brushes on the terminals of the selected trunk. The release of relay 102 also closes a circuit for advancing the 55 sequence switch to position 7 or 16 the circuit being the same that was traced for position 4 or 13.

If all the trunks in a group are busy, the selector brushes travel over the top of the 60 group and rest on the overflow terminals. As there is no ground on the sleeve of the overflow terminals, relay 102 will release and cause the switch to advance to position 7 or 16 in which position relay 102 again operates from ground on cam 130 and locks

to a ground on cam 109 as described hereinbelow advancing the switch to position 8 or 17. In position 8 or 17, a circuit is closed from ground on commutator brush 121 and commutator segment 120, the lower 70 left contact of cam 123, sequence switch magnet 108, battery 112 to ground advancing the switch to position 9 or 18. When the switch advances to position 9 or 18, battery 117 is connected through resistance 116, 75 through left contact of cam 107 over the ring conductor 106 through the district and overflow relay of the sender circuit back over the fundamental tip conductor through the left contact of cam 104, left upper contact 80 of cam 103, contacts 138 and 132 of operated relay 102 to the lower left contact of cam 130 and thence to ground on the district sleeve terminal 114. This circuit advances the sender and district and when the district sleeve is opened, relay 102 releases. The release of relay 102 connects ground to the down drive magnet 136 returning the circuit to normal.

When all the trunks in a group are not 90 busy and the brushes are brought to rest on the terminals of an idle trunk with sequence switch 108 in position 7 or 16, relay 102 operates in a circuit which may be traced from ground through normally 95 closed contact 137 of relay 102, or from the district sleeve and the lower left contact of cam 130, left upper contact of cam 130, left winding of relay 102, right contact of cam 101, right winding of relay 102, resistance 115, battery 117 to ground. The operation of relay 102 again closes a 100 circuit for advancing the sequence switch to position 8 or 17. When operated in position 7 or 16, relay 102 locks to ground 105 at cam 109 over a circuit which may be traced from ground through the left and right upper contacts of cam 109, left lower contact of cam 130, contact 132 of relay 102, left winding of relay 102, right contact of cam 101, right winding of relay 102, resistance 115, battery 117, and thence 110 to ground. In positions 8 to 9 or 17 to 18, relay 102 locks to ground on the sleeve brush of the associated district circuit. In position 8 or 17, the talking circuit is closed 115 through both lower contacts of cam 104 and the upper right contact of cam 107.

At the completion of the conversation, the 120 district selector is disconnected from the office selector opening the circuit through the windings of relay 102 which releases. When relay 102 releases, ground is connected to the sequence switch magnet 108, advancing it to position 9 or 18. In position 9 or 18, ground is connected to down drive magnet 136 energizing the down drive to return the brush shaft to normal. This circuit may be traced from ground through 125 the left contact of cam 109, normally closed 130

contact 122, of relay 102, both lower contacts of cam 125, down drive magnet 136, battery 119 to ground. When brush shaft reaches the bottom of the bank, ground from commutator brush 128 and commutator segment 139 is connected to sequence switch magnet 108 through the upper right contact of cam 123, advancing the switch to normal position 10 or 1.

10 When the brush shaft is driven to tell-tale, a circuit is closed from ground on commutator segment 134 and brush 128 through the left upper contact of cam 123 to battery 112, through sequence switch magnet 108 advancing the switch to position 7 or 16. The operation of relay 102 in position 7 or 16 advances the sequence switch to position 8 or 17. The ground on commutator segment 134 and commutator brush 128 advances the switch to position 9 or 18. From this point on, the circuit functions in the same manner as previously described hereinabove for the overflow condition where all the trunks in a group are busy.

15 The self-returning feature of the sequence switch in a position awaiting a sender for group selection (position 3 or 12) will now be described in detail. Suppose the sequence switch 108 or the selector switch be moved off normal by hand or the sequence switch be advanced to position 3 or 12 falsely with the brush shaft off normal, the commutator brushes being above commutator segment 139, with no district selector connected to the incoming conductors 105, 106 and 114. Relay 102 will operate in a circuit from ground through the lower left and upper right contacts of cam 129, right winding 40 of relay 102, through resistance 115, battery 117 to ground. The operation of relay 102 closes an energizing circuit for sequence switch magnet 108 which may be traced from ground through battery 112, magnet 108, lower right contact of cam 111, contact 110 of operated relay 102, left contact of cam 109 to ground. The sequence switch advances to position 4 or 13 in which position relay 102 releases and the magnet 108 is again operated in a circuit from the left contact of cam 109 through the normally closed contact 122 of relay 102, lower right contact of cam 123, through magnet 108 to grounded battery 112. The switch advances to position 5 or 14 in which position relay 102 again operates in a circuit similar to that traced for position 3 or 12. Sequence switch magnet 108 energizes advancing the sequence switch to position 6 or 15 in which position, relay 102 again releases, whereupon the sequence switch magnet 108 is again energized in a circuit the same as described above for position 4 or 13. The sequence switch advances to position 7 or 16, relay 102 op-

erating in a circuit from ground through battery 117, resistance 115, the right winding of relay 102, right contact of cam 101, left winding of relay 102, upper left contact of cam 130, normally closed contact 137 of relay 102 and thence to ground, relay 102 locking through its windings, the left contacts of cam 130 to ground through the upper right and lower left contacts of cam 109. Sequence switch magnet 108 is energized and advances the sequence switch to position 8 or 17, in which position relay 102 releases, whereupon the sequence switch magnet 108 is energized advancing the switch to position 9 or 18. In position 9 to 18, the down drive magnet 136 is operated in a circuit which may be traced from ground through the left contact of cam 109 to the normal closed contact 122 of relay 102, both lower contacts of cam 125 through down drive magnet 136 to grounded battery 119. The operation of down drive magnet 136 causes the brush shaft to go down to normal. When the brush shaft reaches the bottom of the bank, ground on the commutator brush 128 and segment 139 is connected through the upper right contact of cam 123 to the sequence switch magnet 108 advancing the switch to normal position 1 or 10.

20 What is claimed is:

1. In a telephone exchange system, a calling subscriber's line, a called subscriber's line, automatic means for extending a call from said calling subscriber's line to said called subscriber's line including a selector switch, said switch having progressively operable means individual thereto for controlling two complete cycles of operation thereof during a single complete cycle of said last named means.

2. In a telephone exchange system, a calling subscriber's line, a called subscriber's line, automatic means for extending a call from said calling subscriber's line to said called subscriber's line including a selector switch, said switch having an auxiliary progressively operable switch individual thereto for controlling two complete cycles of operation thereof during a single revolution of said auxiliary switch.

3. In a telephone exchange system, a calling subscriber's line, a called subscriber's line, automatic means for extending a call from said calling subscriber's line to said called subscriber's line including a selector switch, said switch having progressively operable means associated therewith for controlling two complete cycles of operation thereof during a single complete cycle of said last named means, and means associated with said switch including a relay operative in response to an energizing circuit prepared by an abnormal off-normal condition of said switch for automatically

restoring said switch to a normal position.

4. In a telephone exchange system, a calling subscriber's line, a called subscriber's line, automatic means for extending a call from said calling subscriber's line to said called subscriber's line including a selector switch, said switch having a progressively operable switching means associated therewith for controlling the setting and restoration thereof, and means for causing the restoration of said switch including a relay which is repeatedly operated during the advance of said switching means and controls the advance of said switching means to its switch restoring position.

5. In a telephone exchange system, a calling subscriber's line, a called subscriber's line automatic means for extending a call from said calling subscriber's line to said called subscriber's line including a selector switch, said switch having a progressively operable switching means associated therewith for controlling the setting and restoration thereof, and means for causing the restoration of said switch including a relay which initially operates to advance said switching means, the advance of said switching means causing the release of said relay, said release causing the further advance of said switching means, this cycle being re-

peated until said switching means is advanced to its switch restoring position.

6. In a telephone exchange system, a calling subscriber's line, a called subscriber's line, automatic switching means for extending a call from said calling subscriber's line to said called subscriber's line including a selector switch, means associated with said switch for restoring it to normal position, a relay means effective when said switch is moved to an off-normal position and no other of said automatic switching means is connected therewith for operating said relay, and means under the control of said relay for operating said restoring means.

7. In a telephone exchange system, a calling subscriber's line, and a called subscriber's line, a selector switch for extending a connection from said calling line to said called line, a sequence switch associated therewith for controlling its operation, having two normal positions, and means associated with said sequence switch for automatically restoring it to one of said two normal positions from a position to which it has falsely advanced.

In witness whereof, I hereunto subscribe my name this 18th day of November A. D., 1924.

CLARENCE H. BERRY.
